CLAIM

The ornamental design for an aerosol device for large animals, as shown.

DESCRIPTION

FIG. 1 is a perspective view of my design.

FIG. 2 is view of my design as seen from one side.

FIG. 3 shows a mirror image of the opposite side from that shown in FIG. 2.

FIG. 4 is a view looking at the right side of the view shown FIG. 2.

FIG. 5 is a view looking at the left side of the view shown FIG. 2; and,

FIG. 6 is a bottom view of my design.
